UNITED STATES PATENT OFFICE.

WILLIAM H. VOSS, OF DAVENPORT, IOWA.

WASHING-MACHINE MECHANISM.

1,385,806.

Specification of Letters Patent. Patented July 26, 1921.

Application filed July 30, 1917. Serial No. 183,429.

To all whom it may concern:

Be it known that I, WILLIAM H. Voss, a citizen of the United States, residing at Davenport, in the county of Scott and State 5 of Iowa, have invented certain new and useful Improvements in Washing - Machine Mechanism, of which the following is a specification.

This invention relates to washing machines and more particularly to a new and improved form of gearing for operating the same.

Among the objects of my invention is to provide such form of gearing having a shifting clutch whereby when said clutch is suitably manipulated, the washing machine may be opened and closed without stopping the gasolene engine or other source of motive power; to arrange the more dangerous parts 20 of the gearing underneath the tub where they will be out of the way and not liable to catch the clothing of the operator; to so arrange the handle of the clutch that it will be convenient for operation and positive in its action; to provide a new and improved form of clutch mechanism; to provide a form of universal joint connection between the lower end of the operating lever and the outer end of the pitman; to provide 25 a horizontal power shaft which is longitudinally slidable in its bearings in order that in the operation of the clutch the shaft may be shifted longitudinally instead of the drive pinion; to provide a novel arrangement of lever and handle for operating the clutch; and to provide such arrangement of parts as will result in a more simple, less expensive and more efficient apparatus of 30 the class set forth.

40 Further objects and advantages will appear as my invention becomes more thoroughly understood.

My invention further resides in that combination, construction and arrangement of 45 parts illustrated in the accompanying drawings, and while I have illustrated a preferred embodiment therein, I desire it to be understood that the same is susceptible of modification and change without departing 50 from the spirit of my invention.

In the drawings:

Figure 1 is a side elevation of a washing machine embodying my invention.

Fig. 2 is a vertical transverse section 55 through the universal connection between

the lower end of the lever and the connecting rod.

Fig. 3 is a plan view of the under gearing.

Fig. 4 is a side elevation of Fig. 3.

Fig. 5 is a vertical transverse section 60 through Fig. 3, the dotted lines showing the positions of the shaft and pulley when the clutch is disengaged.

Fig. 6 is a section through the power shaft, showing the arrangement of lever for 65 shifting the shaft longitudinally in the operation of the clutch.

Fig. 7 is a detail perspective view of the driving pinion.

Fig. 8 is a fragmentary perspective view 70 of the clutch end of the power shaft.

Referring to the drawings, 1 designates the tub of the washing machine, upon the top of which is mounted the lid 2, secured to which lid is the housing 3, within which 75 is mounted suitable driving mechanism for the dolly (not shown) and which mechanism is actuated by the rack bar 4, the outer end of which is pivotally connected to the upper end of the operating lever or rocker 80 arm 6, which is in turn pivoted to the bracket 7' mounted upon the side of the tub 1. The lower arm 7 of the operating lever is connected by means of the pin 8 to the sleeve 9, which sleeve is fixedly mounted upon the short shaft 10 by the pin 8, which extends entirely through both sleeve 9 and shaft 10. The lower end of the shaft 10 is rotatably mounted in the bearing 11, which is carried by the outer end of the connecting rod or pitman 12, which is composed of the two side members 13, 14, secured within the recesses 15 by means of pins or bolts 16. The bearing 11 is held in position 90 upon the shaft 10 by the washer 17 and cotter key 18.

Suitably secured to the bottom of the tub 1 are the legs 19, extending between which are the cross bars 20, adjacent ends of which are suitably connected together 100 by means of the cross plate 21, which is secured to the cross bars 20 by means of the bolts 22'. Secured to the upper side of the cross plate 21 is the metal plate 22, which may be of cast iron or other suitable 105 material and formed upon the outer end of which is the integral bearing 23, slightly spaced inwardly from which is a second bearing 24 secured to the plate 22 by means of bolts 25'. As will be seen from Fig. 5, 110

the plate 22 is formed with the downwardly extended or offset portion 25, which rests upon the intersecting portions of the cross bars 20 and is provided with the downwardly extending integral sleeve portion 26, within which is rotatably mounted the shaft 27 carried upon the upper end of which is the gear wheel 28, the hub 29 of which rotates within the annular recess 30 formed by the circular rib 31.

Loosely mounted upon the inner end of the power shaft 32, which is slidably mounted in the bearings 23, 24, is the pinion 33, which is provided in its face adjacent the teeth with the inclined offset portions 34, 35, see Fig. 7, each of which portions terminates in the slots or recesses 36, 37, respectively. Formed in the hub of this pinion on the end opposite from the inclined faces is a circumferential groove 38, within which engages the projection 39 carried by the plate 22, the function of which is to permit the pinion to rotate, but at the same time to prevent any longitudinal movement thereof. Extending through the power shaft 32 and adjacent the inclined faces of the pinion is the pin 40, the function of which is (when the power shaft is shifted longitudinally to the left) to engage the inclined faces 34, 35, which faces carry the two ends of the pin into the notches or recesses 36, 37, thus establishing a driving connection between the power shaft and the pinion. Keyed to the opposite end of the power shaft is the belt pulley 41 which is spaced away from the bearing 23 a distance sufficient to permit of such longitudinal movement of the power shaft 32 as to disengage the pin 40 from the notches 36, 37, which disengaged position is indicated by dotted lines in Fig. 5. By shifting the power shaft longitudinally in the appropriate direction, the clutch may be thrown either into or out of operative position as desired.

As a means for shifting the shaft 32 longitudinally, I have provided the elongated collar 42 (see Fig. 6) which carries upon its ends the pins or cylindrical extensions 43, 50 which engage in suitable openings in the outwardly bowed portions 44, 45, of the lever 46. The elongated collar 42 is loosely mounted upon the shaft 32 in order to permit rotation of this shaft therein. The lower ends of the outwardly bowed members 44, 45, are brought together to form the contiguous parallel portions 47, 48, which at their lower ends fit into the aperture 49 in the up-standing projection 50, 60 which up-standing projection is formed integral with the plate 22, the purpose of which aperture is to hold this end of the lever against any substantial movement therein, and yet act as a fulcrum therefor.

65 The outwardly bowed members 44, 45, are

brought together at their upper ends to form the parts 51, 52 which are secured together by the bolt 53, beyond which they are again slightly outwardly sprung to provide the space 54 within which is secured 70 by means of the cotter key 55 the end 56 of the handle extension 57, upon the outer end of which is secured by means of the bolts 58 extending through the elongated slots 59, the handle portion 60 provided on its lower 75 surface with notches 61 and 62 to fit over a suitable projection mounted on the tub legs as desired. This handle 60 may be either grasped by the hand of the operator when shifting the clutch, or it may be operated 80 by means of any suitable extension or lever secured thereto as desired, and mounted in any suitable manner to the side of the tub.

Referring to Fig. 5, it will be seen that in order to prevent the longitudinal slipping of the elongated collar 42 on the power shaft, I have provided washers 63, 64, which are held in place upon opposite sides of the collar 42 by means of suitable cotter keys or pins 65. Secured to the outer end of 90 one of the arms of the gear 28 is the crank pin 66, see Fig. 3, upon which is rotatably mounted the bearing 67 carried by the inner end of the connecting rod and suitably secured between the side members 13 and 14 95 thereof. In order to provide for a certain amount of vertical oscillation of the connecting rod, I have interposed at the inner end of the members 13, 14, the pin connection 67', which thus gives a universal connection somewhat similar to that given to the outer end of the connecting rod and the lower end of the operating lever. In case it is desired to operate the machine by hand, a suitable handle may be inserted within the 100 socket 68 formed on the upper end of the arm 5 of the operating lever, and in case it is desired to operate the machine entirely by hand, it is obvious that a suitable fly wheel may, if desired, be substituted for 110 the belt pulley 41. However, the greater value in my improved mechanism resides in the use of the belt wheel for the reason that it will permit of the disengagement of the operating parts of the under gearing, as a 115 result of which the lid of the tub may be raised without stopping the gasoline engine or other motor.

In the operation of my improved gearing, rotary motion is transmitted to the power 120 shaft 32 from the belt pulley 41. Assuming that the power shaft and related parts occupy the position shown in dotted lines in Fig. 5, and it is desired to start the mechanism, all that is necessary is to push on the 125 handle 60, which will move the lever 46 in Fig. 5 to the left, thus carrying the pin 40 on the end of the shaft 32 into engagement with the beveled surfaces 34, 35, as a result of which the pin 40 will be at once carried 130

at its respective ends into the slots 36, 37, thus connecting the power shaft and the pinion firmly together. This will in turn transmit motion to the gear 28 and through 5 the connecting rod or pitman 12 to the operating lever 6, and thus in turn to the washing mechanism carried by the lid of the tub. If the machinery is in operation, and it is desired to stop the same, an outward pull on 10 the handle 60 will move the lever 46 in Fig. 5 to the right, thus longitudinally sliding the shaft 32 within its bearings, which will result in a disengagement of the pin 40 from the slots 36, 37, in the pinion, after which 15 the lid of the tub may be raised safely, for the reason that the upper part of the mechanism will no longer be in motion.

By virtue of the universal connections between the lower end of the operating lever 20 and the connecting rod and the inner end of this connecting rod and the crank pin on the gear 28, it will be seen that there will be no undue strain or twisting between these parts. This is very important, for the reason that 25 the connecting rod 12 is given a slight up and down movement at its outer end as well as a rotary movement at its inner end, and in the absence of this improved form of joint, would result in a twisting or undue 30 straining of these parts. As a result of my invention in this respect, these parts will have a perfectly free and easy operation.

Having now described my invention, I claim:—

35 1. In apparatus of the class described, a support, an operating lever pivoted to the side of said support, a horizontal power shaft slidably mounted beneath said support, a pinion on said shaft, a single means connected with the support and engaging the pinion to prevent longitudinal movement thereof in either direction but permitting 40 rotary movement thereof, a gear driven by said pinion, connecting means between said 45 gear and said lever, and a clutch mechanism

associated with said pinion, whereby the same may be thrown into or out of operation upon longitudinal movement of said shaft.

2. In combination, a support, a plate on said support having a bearing, a power shaft 50 mounted for longitudinal sliding movement in said bearing, a pinion loosely mounted on said shaft and having a circumferential groove, means to engage and drive said pinion upon longitudinal movement of said shaft, an arm on said plate engaging said groove to prevent longitudinal movement of the pinion but permit rotation thereof, and a gear operatively connected with said pinion, whereby to operate a driven mechanism 55 when said shaft is moved longitudinally into driving engagement with said pinion.

3. In apparatus of the class described, a support, a top mechanism on said support, means for operating said top mechanism including a lever pivoted on the side of said support, a horizontal power shaft slidably mounted beneath said support, a pinion loosely mounted on said shaft and provided with clutch parts, a projection on said shaft 60 for engagement with one of said clutch parts when said shaft is shifted longitudinally, means for shifting said shaft, and a horizontal gear engaging said pinion and operatively connected with said lever, whereby 65 said top mechanism may be operated.

4. In apparatus of the class described, a support, a lever pivoted to the side of said support, a pitman beneath said support, and a universal connection between said lever 80 and said pitman comprising a vertical bearing formed in the end of said pitman, a sleeve seated on the upper edge of said bearing, a shaft pinned in said sleeve and rotatably mounted in said bearing, and said lever 85 having pin connection with said sleeve.

In witness whereof, I hereunto subscribe my name to this specification.

WILLIAM H. VOSS.
